ROTARY PISTON ENGINE

Manuel E. Puim, Los Angeles, Calif.

Application January 7, 1955, Serial No. 480,348

1 Claim. (Cl. 123—16)

This invention generally relates to internal combustion engines and it has specific relation to engines of the rotary type embodying a member rotatably mounted eccentrically in a cylindrical casing and provided with a plurality of sliding pistons cooperating with the inner surface of the cylindrical casing for successively drawing in or receiving a combustible mixture, compressing the same, forcing the compressed combustible mixture into a firing chamber, igniting the compressed combustible mixture, receiving the propelling force of the combustion of the explosive mixture and finally expelling the burnt gases from the interior of the casing.

An object of this invention is to provide a rotary type piston engine of improved construction, increased efficiency, very few moving parts, simplicity and extreme reduction in friction.

A further object of the present invention is to provide a rotary piston engine in which alternate pistons are driven by the firing of a charge of combustible mixture behind the pistons after it has been compressed in which the area of the surface of the piston acted upon by the expanding gases increases as the force of the gas decreases and wherein the combustion chamber or firing chamber is provided with a high pressure exhaust port to decrease the load imposed upon the succeeding piston in expelling the burnt gases from the firing chamber.

Still another important object of the present invention is to provide a rotary type piston motor that utilizes a super charger for compressing the combustible mixture before it enters the engine and forming a device having two power strokes per revolution of the rotor.

Yet another important feature of the present invention is to provide a rotary type piston engine wherein two rigid and elongated pistons are provided in crossed relation in sliding engagement with the rotor wherein both ends of each piston will be continuously in contact with the inner surface of the cylindrical casing thereby eliminating the friction normally caused by centrifugal force urging the vane type pistons against the surface of the casing as it will be seen that the centrifugal forces acting upon the elongated pistons utilized in the present construction substantially neutralize each other.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the rotary piston engine of the present invention;

Figure 2 is a vertical, sectional view on an enlarged scale taken substantially upon the plane taken along section line 2—2 of Figure 1 showing the details of construction of the engine of the present invention;

Figure 3 is a transverse, vertical sectional view taken substantially upon a plane passing along section line 3—3 of Figure 2 showing further structural details of the interior of the engine of the present invention;

2

Figure 4 is a plan sectional view taken substantially upon a plane passing along section line 4—4 of Figure 2 showing the details of construction of the firing chamber;

Figure 5 is an exploded group perspective view showing the rotor and the two pistons mounted therein; and

Figure 6 is a group perspective view showing the sealing members on the outer ends of the pistons for engaging the side surfaces of the cylindrical casing as well as the inner peripheral surface thereof.

10 Referring now specifically to the drawings, it will be seen that the numeral 10 generally designates the rotary piston engine of the present invention including a generally hollow cylindrical casing designated by the numeral 12 and including two cylindrical side members 14 and 16 and a peripheral member 18. The peripheral member 18 is formed integrally with a supporting base 20 that may be attached to any supporting surface. Also integrally formed with the center peripheral member 18 is an intake member 22 having an attaching flange 24 and an exhaust opening 26 having an attaching flange 28 for permitting inlet and exhaust into the casing 12. Rotatably supported in the side members 14 and 16 and extending through the casing 12 is a shaft 30 having a rotor or cylindrical member generally designated by the numeral 32 secured thereto for rotation within the casing 12 in an eccentric manner for a purpose described hereinafter. On one end of the shaft 30 is mounted a power take-off belt pulley 34 and on the other end of the shaft 30 is mounted a fan member 36 rotatable in a casing 40 having a discharge conduit 42 integrally formed therewith and attached to the flange 24 of the inlet opening 22 thereby partially compressing the combustible mixture as it enters the intake port 22. The carburetor and fuel supply are not shown in the present illustration and it will be understood that any particular type may be utilized. Secured to the shaft 30 in spaced relation to the pulley 34 is a cam member 44 for operating a valve push rod 46 for a purpose described hereinafter. Adjacent the other end of the shaft 30 is a gear 48 for driving a gear 50 on a magneto 52 that is connected to a spark plug 54 by an ignition wire 56 for operation in a manner described hereinafter.

The rotor 32 includes a pair of generally cylindrical side members 58 and 60 that are secured together by bolts 62 and include transverse recesses 64 on the inner side surfaces thereof and peripheral recesses 66 on the outer surface thereof. Each of the side members 58 and 60 is provided with a central aperture 68 for receiving the shaft 30.

50 Slidably received in the transverse recesses 64 is a pair of elongated pistons 70 and 72 that are provided with recessed portions 74 and 76 on their inner surfaces wherein the recessed portions 74 and 76 are positioned over each other for positioning the pistons 70 and 72 in crossed relationship and slidable relationship in relation to the side members 58 and 60. The recessed portions 74 and 76 are provided with elongated slots 78 and 80 for positioning over the shaft 30 thereby permitting sliding movement of the pistons 70 and 72 in relation to the side members 58 and 60.

60 Each end of each of the pistons 70 and 72 is provided with a notch 82 which extends around three sides of the piston and receives two L-shaped members 84 and 86 which act as seals. The L-shaped members 84 and 86 are provided with springs 88 for urging the vertical legs of the L-shaped members 84 and 86 against the surface of the casing 12. The outer ends of the L-shaped members 84 and 86 overlap for forming a seal against the inner surface of the peripheral member 18 of the casing 12.

70 Remotely from the inlet opening 22 and the exhaust opening 26 is a firing chamber generally designated by the numeral 90 and including an opening 92 providing communication into a chamber 94 which is provided with

an opening 96 back into the interior of the casing 12. The opening 92 is provided with a ball check valve 98 for closing the communication with the interior of the casing 12 through the opening 92 when the spark plug 54 is actuated for firing the combustible mixture that is compressed into the firing chamber 94. A poppet type valve 100 extends into the chamber 94 and is actuated by the push rod 46 through a bellcrank member 102 engaging the outer end of the poppet valve 100. A valve spring 104 surrounds the shank of the valve 100 for urging the valve 100 to a normally closed position. A pair of peripheral sealing rings 106 are positioned in the inner surface of the side members 14 and 16 forming the casing 12 for sealingly engaging the rotor 32 thereby eliminating leakage of compressed gases.

In operation, the rotation of the rotor 32 is clockwise while viewing Figure 2 and the combustible mixture is drawn into the intake 22 or forced under pressure into the interior of the casing 12 by the fan 36. The combustible mixture is then compressed and moved upwardly by the lower piston 70 as illustrated in Figure 2 wherein the gas is forced into the firing chamber 94 through the opening 92 by raising the check valve 98 off its seat. The piston 72 following the bottom piston 70 as viewed in Figure 2, will pick up a second charge of combustible mixture and force it into the chamber 94 in the same way. At this time, the magneto 52 is so timed that it will ignite the combustible mixture and the valve 100 will be opened by the cam 44 thereby permitting the combustion gases to expand into the chamber designated by the numeral 110 which is an expansion chamber for contact against the piston which has just finished compressing. After the gases have expanded, they will then be exhausted through the outlet 26 in the usual manner. The sliding motion of the pistons 70 and 72 in relation to the rotor 32 permits the pistons to at all times seal against the casing 12 and the expanding exhaust gases hit alternating pistons and the other elongated piston acts only as a supercharger or initial compressor for the combustible gases. Lubrication is fed into the interior of the casing with the combustible mixture and the various sealing means provide an efficient combustion and expansion operation.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

A rotary combustion engine comprising a cylindrical stationary, closed casing, an eccentrically disposed rotor

5 in said casing journaled for rotation, the eccentricity of the rotor forming an expansion chamber between the casing and rotor, said casing having a firing chamber thereon, combustible mixture supply means communicated with said chamber, means for admitting a combustible mixture into the chamber, timed ignition means for igniting the combustible mixture, timed valve means communicated with the interior of the casing for permitting the combustion products to expand into the casing, said rotor including a pair of facing plates, the inner surface of each facing plate having perpendicular diametric grooves, the periphery of said plates having an inwardly extending notch at each end of each groove, means detachably securing the plates together in abutting engagement, a pair of perpendicular pistons slidably disposed in said radial grooves with the length of the pistons being substantially equal to the diameter of the casing for engagement with the inner surface of the casing, each piston having a reduced central portion with a slot therein, the reduced portion being slidably disposed in said grooves with the slots being disposed in registry with each other, a power shaft extending through said rotor and the registered slots for permitting movement of the pistons in relation to the rotor, each piston having laterally enlarged ends slidably received in said notches, and terminating in substantially coplanar relation with the outer surface of said plates, each enlarged end having a groove extending across each end and radially inwardly on each side thereof, a pair of L-shaped sealing members disposed in said grooves with one leg disposed in the end groove for engagement with the inner periphery of the casing and the other leg disposed in the side groove for engagement with the end wall of the casing, spring means disposed between the other leg and the bottom of the side groove for urging the sealing members outwardly into engagement with the end walls of the casing with centrifugal force urging said one leg into sealing engagement with the inner periphery of the casing, said one leg being disposed in overlapping relation, said casing having an exhaust opening in the expansion chamber for exhausting expanded exhaust products, said firing chamber directing combustion products against the end of a piston as it travels toward the exhaust opening in the expansion chamber whereby the expansion of the combustion products will cause rotation of the rotor.
